CLOTH-CLAMP.

1,116,630.

Specification of Letters Patent. Patented Nov. 10, 1914.

Application filed May 28, 1914. Serial No. 841,453.

To all whom it may concern:

Be it known that I, WILLIAM S. ROWLEY, a citizen of the United States, and resident of Palmyra, county of Burlington, and 5 State of New Jersey, have invented an Improvement in Cloth-Clamps, of which the following is a specification.

The object of my invention is to provide a form of cloth clamp suitable for use with 10 cloth finishing machines, such as tentering machines employed to work and stretch the cloth to even width and uniform finish, in which the clamp shall be capable of receiving and gripping the selvage without 15 injury thereto. Heretofore, cloth clamps have been made with a gripping jaw whose time of action has been controlled by a pivoted finger resting on the cloth and so operating that when the selvage is withdrawn from 20 under said finger it drops through a slot in the clamp plate and allows the clamping jaw to close upon the selvage of the fabric to hold it. In clamps of this character, the fabric is pressed into the slot of the clamp 25 plate and is drawn against the edges thereof with detrimental result, consisting in roughening the surface, longitudinally stretching the selvage and ironing it over said abrupt edges of the slot with the production of a wavy fullness, which, because 30 of the heated condition of these clamps, is objectionable in weakening the cloth and its selvage by overheating in cases where the fabric is of a delicate texture, such as in thin 35 silk goods. By my improvements, these objections are entirely overcome and the selvage of the finished fabric is smooth and of a uniform finish with the rest of the goods.

My invention consists of a cloth clamp 40 having a clamp plate over which the fabric is drawn and upon which it is clamped, and in which clamp plate there is a slot for the controlling finger, said slot having a beveled or inclined side or sides to provide a depression above the slot over which the cloth 45 floats in supporting said controlling finger, whereby the cloth may perform its function to hold the clamping jaw out of gripping operation through the action of the 50 controlling finger and without being pressed against the abrupt edges of the slot in the clamp plate. The clamp plate is provided with a depression wider than the slot and the slot opens from the bottom of the 55 depression.

My invention also comprehends details of construction which, together with the features above specified, will be better understood by reference to the drawings, in which:—

Figure 1 is a transverse sectional view on line $\alpha-\alpha$ of Fig. 2 of a cloth clamp embodying my invention; Fig. 2 is a longitudinal sectional view of the same on line $\gamma-\gamma$ of Fig. 1; and Fig. 3 is a sectional view of a modified form of a portion of my invention.

2 is a link, by which a plurality of clamps may be connected to form a chain, in the well known manner for use in tentering 70 machines. This link is provided with a transverse body 3 having a vertical aperture 4 above the link and a pair of overhanging arms 8. The body 3 is covered with a brass or other non-rusting plate 5, 75 having a narrow slot 6 opening into the aperture 4; and the surface of the said plate adjacent to the slot is beveled or inclined downward as at 7 so that there is a decided depression in the surface of the plate above 80 the slot and on the opposite sides thereof. The purpose of this depression of the plate surface is to prevent the fabric F from being pressed against the edges of the slot 6 in the act of its being adjusted within the 85 clamp preliminary to being clamped on its selvage. This purpose and the manner in which it is effected will be described later on in the specification.

9 is the clamping jaw and is loosely journaled on the longitudinal pin 11, which extends through and is carried by the overhanging arms 8. The lower edge of the jaw 9 is made with a reasonably sharp clamping edge 10 to positively grip the 95 fabric; and there is an upwardly extending arm 12 to the jaw which is adapted to be actuated by a cam on the machine during the travel of the clamp, to rock the clamping jaw 9 at times of receiving the cloth and discharging it from the clamp. The clamping jaw is further provided with a rearward arm 13 to which is hinged, at 16, a controlling finger 14, the rear lower edge of which rests upon the plate 5 of the body and the 100 forward edge 15 of which rests upon the cloth F just prior to clamping the same (Fig. 1). This controlling finger 14 is narrow enough to work downward through the slot 6 of the plate 5. As shown in Fig. 1, 110

the cloth F is over the slot 6 and is supporting the finger 14 at one end, while the other end is fulcrumed on the plate 5 and in this manner supports the clamping jaw 9 out of 5 gripping action. When the cloth is pulled outwardly, or to the right in Fig. 1, it will liberate the finger 14 and the end 15 will drop down through the slot 6; this will remove the support for the clamping jaw 9 10 and it will drop just in time to grip the selvage of the cloth.

The general operation of a clamp of this nature is not new, but it has been found in commercial use that with the slot 6 through 15 the plate 5 and extending up to the uniform top surface, the pressure of the controlling finger 14 caused the cloth to be pressed against the sharp or abrupt edges of the slot and injured it, and especially was this 20 so, in aggravated form, when the clamps were hot, as is necessarily the case in certain kinds of finishing. To overcome this serious defect in the old style of clamps, when employed in finishing delicate light weight 25 grades of cloth, I have provided a construction in which the cloth does not come into contact with the sharp or abrupt edges of the slot. It will be seen from the drawings that the cloth is supported from contact 30 with the plate 5 above the slot 6; and even if it sags slightly it will meet an inclined guide surface 7 instead of an abrupt shoulder of the slot. As shown, the clamp is made so that it may run in either direction 35 but it will be understood that, if desired, the inclined depressed portion 7 may be only on the side to which the cloth would be drawn; and it is to be understood that the shape of the surface may be greatly varied, 40 as for example in Fig. 3, in which the slot 6 in the plate is formed by splitting the plate and bending down the metal on each side of the split. This latter will form a shorter depression which the cloth will have 45 to bridge, but its action will be substantially the same as in the other case.

The general construction of the cloth clamp may be varied, as my invention is adapted to any clamp having the clamping 50 jaw supported by a pivoted or movable part sustained by the fabric in the act of clamping the selvage of the fabric, and I therefore do not restrict myself to the details here shown.

55 Having now described my invention, what

I claim as new and desire to secure by Letters Patent, is:

1. In a cloth clamp, a body having a plate for supporting the cloth provided with a slot and formed with a depression of space 60 wider at the top than the width of the slot, combined with a pivoted clamping jaw, and a controlling finger for supporting the clamping jaw out of clamping action arranged to enter the slot but adapted to be 65 held out of the slot by the cloth and to act upon the cloth at a distance from the bounding edge of the space above the slot.

2. In a cloth clamp, a body having a plate for supporting the cloth provided with a 70 slot having its side walls terminating at a distance below the surface of the plate and connected with said surface by inclined portions providing a depression in the surface of the plate above the slot thereof, combined with a pivoted clamping jaw, and 75 controlling means therefor providing a finger arranged to move down into the slot and adapted to be supported by the cloth preliminary to its being clamped.

3. In a cloth clamp, a body having a plate for supporting the cloth provided with a slot having its side walls terminating at a distance below the surface of the plate and connected with said surface by long oppositely inclined portions providing a shallow 85 depression in the surface of the plate deepest at a point above the slot thereof, combined with a pivoted clamping jaw, and controlling means therefor providing a finger 90 arranged to move down into the slot and adapted to be supported by the cloth preliminary to its being clamped.

4. In a cloth clamp, a body having a plate for supporting the cloth, said plate having 95 a depression in its surface and a slot opening through the plate arranged at the bottom of the depression, combined with a pivoted clamping jaw, and controlling means having a finger adapted to move through the slot 100 but supported by the cloth when above the depression to hold the jaw from clamping the cloth until the finger is released.

In testimony of which invention, I hereunto set my hand.

WM. S. ROWLEY.
